UNITED STATES PATENT OFFICE.

GOUVERNEUR GRAHAM BROWNE, OF OAKMONT, PENNSYLVANIA.

PRESS.

Application filed April 20, 1921. Serial No. 462,956.

To all whom it may concern:

Be it known that I, GOUVERNEUR G. BROWNE, a citizen of the United States, and a resident of Oakmont, in the county of Allegheny and State of Pennsylvania, have invented a new and useful Improvement in a Press, of which the following is a specification.

My invention relates to presses for up-
setting metal and punching out a ring or
washer therefrom, and has for its principal
object to devise a press which can perform
a plurality of operations on a bar or other
metal stock without requiring the stock to
be moved between operations. Another ob-
ject is to use the movable die for limiting
the feed of the stock. Other objects of the
invention will appear hereinafter.

The invention consists principally in a
hydraulic press having a hollow plunger
which is itself adapted to constitute a cylin-
der for a second plunger. The invention
further consists in providing means for
limiting the backward movement of the
plungers, whereby the die faces thereof can
be used to limit the amount of feed of the
stock; it also consists in the parts and com-
binations of parts hereinafter described and
claimed.

In the drawings wherein like reference
characters refer to like parts wherever they
occur,

Fig. 1 is a longitudinal sectional view of
a press embodying my invention, along the
line 1—1 in Fig. 2;

Fig. 2 is a top plan view thereof;

Fig. 3 is an end view thereof;

Fig. 4 is a fragmentary sectional view
similar to Fig. 1, having a modified form of
hollow plunger; and

Fig. 5 is a cross-sectional view thereof.

Mounted on a suitable base 1 is a hollow
cylinder or chamber 2, in which works a
hollow plunger 3. Said hollow plunger is
closed at the rear end and open at the front
end and constitutes a cylinder for a second
plunger hereinafter described. The cylinder
2 is provided with an annular shoulder 5
against which the flanged end portion 6 of
a bushing 7 for the plunger 3 abuts. An-
other bushing 8 is arranged at the forward
end of the cylinder 2, with its end spaced
away from the bushing 7. A suitable pack-

ing 9 is arranged to fill the gap between the
ends of said bushings. A clamping ring 10
is secured to the open end of the cylinder 2,
preferably by bolts 11, and holds the bush-
ing 8 in place. The cylinder is provided
with an opening 12 which is connected with
a fluid supply pipe 13. Said pipe 13 is
connected with the main supply pipe and
also with an intensifier 13^a which supplies
fluid under higher pressure than the main
supply pipe. Suitable valves 13^b are pro-
vided for controlling the connections be-
tween said supply pipe 13 and the two
sources of fluid pressure.

An opening 14 through the closed rear
end 15 of the hollow plunger 3 forms a
passageway connecting the interior of the 70
cylinder 2 with the interior of the hollow
plunger 3. A collar 16 is disposed in the
open end of said hollow plunger 3, and is
preferably secured thereto by bolts 17. An
annular die holder 18 is secured to the face 75
of said collar 16 by bolts 19 or the like.
The face of said die holder 18 is recessed
to receive an annular die 20 which is se-
cured thereto, as by bolts or screws 21. A
metal ring 22 is disposed around said die
20 and is suitably secured to the die holder
18. A stop ring 23 having radially dis-
posed projections or lugs 24 is secured to
said metal ring 22. The space between said
lugs make it possible to see the work being
acted upon by the die.

A plunger 25 is disposed inside of the
hollow plunger 3. Bushings 26 similar to
the bushings 7 and 8 above described abut
against shoulders 27 on the plunger 25 and
are disposed with a gap between them,
which is filled with suitable packing 28. A
clamp ring 29 for said bushings is secured
to said plunger 25, as by bolts 30. The
plunger head 31 is comparatively long and
is slidable in the collar 16 and in the die
holder 18 and die 20. Suitable bushings 32
and packing 33 for said plunger head 31
are arranged in the collar 16. A passage-
way 34 through said collar 16 is connected
with a fluid supply pipe 35 and opens into
the interior of said hollow plunger 3. A
die or punch 36 is secured to the end of
the plunger head 31, as by a threaded pro-
jection 37 which fits into a threaded hole
provided therefor in the end of the plunger

head. The die 36 fits closely in the opening of the die 20 and when the plunger 25 is in its rearmost position in said hollow plunger the face of its die 36 is flush with 5 the face of the die 20.

A work plate 38 on which a bar 39, or other metal stock rest in position to be acted on by the plunger 25 and the hollow plunger 3 is mounted on a base or frame member 40 10 that is alined with the base 1. Tie bars 41 connect the base 40 with the base 1.

A clamping cylinder 42 has a plunger 43 therein that is arranged to move against the work 39 to clamp it on the work plate 38. 15 A clamp plate 44 is secured to the end of said plunger 43 by bolts or screws 45 and constitutes the bearing surface of the plunger 43 that engages the bar 39. A die 46 having a semi-circular recess in its lower 20 edge to accommodate the bar 39 is secured to the end of the clamp plate 44. A similar die 47 is secured to the end of the work plate 38.

The clamping cylinder 42 is provided with 25 an opening 48 which is connected with a fluid supply pipe. Suitable bushings 49 and packing 50 in said cylinder fit snugly around said plunger 43.

Diametrically opposed rods 51 are threaded 30 into the top of the plunger 43 and project through holes provided therefor in the closed end of the cylinder 42. An auxiliary clamping cylinder 52 having a plunger 53 arranged therein is disposed in alinement 35 with said cylinder 42. Suitable packing 54 is interposed between said plunger 53 and auxiliary clamping cylinder 52. On the end of said plunger 53 is a yoke 55 which is provided with holes through which the 40 threaded ends of the rods 51 project. By means of nuts 56, the position of the yoke 55 on said rods 51 can be adjusted. The auxiliary clamping cylinder 52 is provided with an opening 57 which is connected with a 45 fluid supply pipe.

Rods 58 are threaded into the closed end 50 of the clamping cylinder 42 and project longitudinally therefrom. Adjustably secured to the ends of said rods 58 by nuts 59 is a yoke 60. Said rods 58 are arranged so that the yoke 60 is beyond and substantially at right angles to the yoke 55; so that the return movement of the plunger 43 is limited thereby.

An auxiliary cylinder 61 is mounted with 55 its closed end abutting against the closed end of the cylinder 2. An auxiliary hollow plunger 62 open at one end is arranged 60 open end foremost in said auxiliary cylinder 61. Said cylinder 61 is provided with an opening 63 which is connected with a fluid pipe 64. Said hollow plunger 62 is also provided with an opening 65 near its end, which is connected with a pipe 66 which 65 leads to the pipe 35 of the collar 16. The

communication between said auxiliary hollow plunger 62 and the interior of said hollow plunger 3 is always kept open and fairly constant pressure is maintained in said auxiliary hollow cylinder 61 while the machine 70 is in operation.

Said plunger 62 has a cross-head 67 on the end thereof which is provided with holes through which pass rods 68 which are secured to the end of the plunger 3 and pass 75 through holes provided therefor in the end of the cylinder 2. Said cross-head 67 is adjustably held on said rods by nuts 69.

A limit stop is provided for the plunger, comprising rods 70 projecting from the end 80 of the main cylinder 2 above and below said auxiliary cylinder 61 respectively and having a cross piece 71 adjustably secured thereto near their outer ends, as by nuts 72. The stop limits the return movement of the plunger and thus enables the face of the plunger 3 to limit the amount of feed of the bar 39.

In the slightly modified construction 85 shown in Fig. 4 a hollow nose piece 80 flares 90 at one end and is secured to the end of the hollow plunger 3. Preferably the nose piece 80 is composed of separate members secured together by bolts 80^a. The flaring portion 95 of the nose piece is skeletonized or provided with openings 81 which give easy access to the end of the hollow plunger, making it easy to repair or replace the packing ring. The nose piece 80 is provided with fins 82 to which are secured cross arms 83 which 100 have curved end portions 84 which engage the bars 41 and thus serve to guide and brace the hollow plunger 3. The die 20 is mounted in a suitable recess in the nose piece 80.

The operation of the press is as follows:

Assuming that both plungers 3 and 25 are 110 in their rearmost positions, the metal stock bar 39 is advanced until it strikes the face of the die 36 and water under pressure is then allowed to enter the clamping cylinder 42, moving the plunger 43 and clamp plate 44 towards the work, causing the latter to engage the bar 39 and hold it firmly on the work plate 38. Fluid is then allowed to enter the main cylinder 2 under comparatively low pressure, say 1500 pounds per square inch. The hollow plunger 3 is thereby driven forward, carrying with it the smaller plunger 25 and the pressure is transmitted through the two dies 20 and 36 against the end of the bar which is upset thereby. The upset end is substantially circular. Ordinarily it is not essential that the shape of the upset end be exactly circular. When the hollow plunger 3 completes its stroke, water under pressure is allowed to enter the auxiliary clamping cylinder 52 and the pressure in the clamping cylinder 42 is relieved, thus causing the 115 120 125 130

auxiliary plunger 53 to move slightly away from the work, together with the plunger 43 and clamp plate 44. The peripheral portion of the upset end of the bar is held between the annular die 20 and the dies 46 and 47. The inside plunger 25 continues its forward movement after the hollow plunger has stopped, pushing back the bar 39, and punching out a ring. The fluid pressure in the main cylinder 2 may be increased to, say, 6000 pounds per square inch in order to drive the plunger 25 forward more effectively. The fluid pressure in the main cylinder 2 is then relieved, and the fluid pressure in the auxiliary cylinder 61 causes the auxiliary hollow plunger 62 to move back, carrying with it the large hollow plunger 3, until said auxiliary plunger 62 strikes the yoke 71. The fluid pressure is transmitted through the pipes 66 and 35 and the passageway 34 into the interior of the hollow plunger 3 and causes the inside plunger 25 to move to its innermost position in the hollow plunger 3. As the inside plunger moves back, the ring which was punched out, drops off of the end thereof.

A press of the kind above described is economical both of labor and material. The work does not have to be moved between the operation of upsetting and that of punching and is always held in proper position for the punching operation. By means of the adjustable limit stop, the face of the plunger can be made to serve as a limit for the feed of the work, thus making it certain that the proper portion of the stock will be upset.

It is obvious that numerous changes may be made without departing from my invention, and I do not wish to be limited to the precise construction shown.

What I claim is:

1. A press comprising a cylinder communicating with a source of fluid pressure, a hollow plunger in said cylinder constituting a cylinder for a second plunger and having an opening in its back portion communicating with a source of fluid pressure, a second plunger in said hollow plunger, means for holding a bar or the like in position to be operated on by said plungers, and means for controlling the supply of fluid pressure to said cylinders to cause said plungers acting together to upset the end of said bar and then to cause said second plunger to punch out a ring from said upset portion.

2. A press comprising a cylinder communicating with a source of fluid pressure, a hollow plunger therein, the interior of said hollow plunger communicating with said cylinder, a second plunger in said hollow plunger, releasable clamping means adapted to hold a metal bar or the like while it is being operated on by said plungers acting together, means for releasing said

clamping means and means for controlling the fluid pressure to cause one of said plungers to operate on said bar alone.

3. A press comprising a hollow cylinder, a hollow plunger therein closed at one end, a passageway through said closed end communicating with said cylinder, a second plunger in said hollow plunger and means for supplying fluid under pressure to said cylinder to operate both of said plungers.

4. A press comprising a hollow cylinder, a hollow plunger therein closed at one end, a passageway through said closed end communicating with said cylinder, a second plunger in said hollow plunger, means for supplying fluid under pressure to said cylinder to operate both of said plungers, and means for limiting the movement of said hollow plunger and controlling said fluid pressure to operate said second plunger alone.

5. A press comprising a cylinder communicating with a source of fluid pressure, a hollow plunger in said cylinder adapted to constitute a cylinder for a second plunger, said hollow plunger having a hole through its rear end, and said hollow plunger having a collar arranged in its open end, said collar having a passageway therein opening into the interior of said hollow plunger and communicating with a source of fluid pressure, a second plunger in said hollow plunger, means for controlling the communication between said cylinder and said source of fluid pressure to operate both of said plungers, and means for controlling said communication to relieve the pressure in said cylinder whereby the fluid pressure on said second plunger causes it to return in said hollow plunger.

6. An upsetting press comprising a cylinder communicating with a source of fluid pressure, a hollow plunger in said cylinder itself constituting a cylinder for a second plunger and communicating with said cylinder, a second plunger in said hollow plunger, releasable means for holding metal stock in position to be operated on by said plungers, means for controlling the communication between said cylinder and said source of fluid pressure to move said plungers forward to operate on said bar, means for controlling the communication between said cylinder and said source of fluid pressure to cause said hollow plunger to move forward with said second plunger in its rearmost position therein, means for releasing said clamping means, and means for increasing the fluid pressure in said cylinder to move said second plunger forward in said hollow plunger against said stock while the periphery thereof is held by the end of said hollow plunger.

7. An upsetting press comprising a cylinder communicating with a source of fluid

pressure, a hollow plunger in said cylinder, itself constituting a cylinder for a second plunger and communicating with said cylinder, a second plunger in said hollow plunger, said cylinder communicating with a second source of fluid pressure in front of the forward position of said second plunger, releasable means for holding metal stock in position to be operated on by said plungers, 5 means for controlling the communication between said cylinder and said source of fluid pressure to move said plungers forward to operate on said bar, means for controlling the communication between said cylinder 10 and said source of fluid pressure to cause said hollow plunger to move forward with said second plunger in its rearmost position therein, means for releasing said clamping means, means for controlling the fluid pressure in said cylinder to move said second plunger forward in said hollow plunger against said stock while the periphery thereof is held by the end of said hollow plunger, and means for relieving the pressure in said 15 cylinder, whereby the pressure in said hollow plunger causes said second plunger to return to its rearmost position therein.

8. An upsetting press comprising a cylinder communicating with a source of fluid pressure, a hollow plunger in said cylinder, itself constituting a cylinder for a second plunger and the interior thereof communicating with said cylinder, a second plunger in said hollow plunger, said hollow plunger 20 communicating with a second source of fluid pressure in front of the forward position of said second plunger, releasable clamping means for holding a bar in position to be operated on by said plungers, means for controlling the communication between said cylinder and said source of fluid pressure to cause said plungers to move forward to operate on said bar, means for controlling the communication between said cylinder 25 and said source of fluid pressure to move said hollow plunger forward with said second plunger in its rearmost position therein, means for increasing the fluid pressure in said cylinder to move said second plunger forward in said hollow plunger against the work while the periphery of said work is held by said hollow plunger, means for controlling the communication between said cylinder and said source of fluid pressure to 30 relieve the pressure in said cylinder, an auxiliary cylinder alined with said first mentioned cylinder and communicating with a source of fluid pressure, an auxiliary hollow plunger in said auxiliary cylinder, said auxiliary hollow plunger being connected with said first mentioned hollow plunger, said auxiliary plunger being forced back by the fluid pressure in said auxiliary cylinder when the pressure in the main cylinder is 35 relieved, thereby returning said hollow

plunger to its rearward position in said main cylinder.

9. An upsetting press comprising a cylinder communicating with a source of fluid pressure, a hollow plunger therein, itself constituting a cylinder for a second plunger and communicating with said cylinder, a second plunger in said hollow plunger, an auxiliary cylinder alined with said first mentioned cylinder and communicating with a constant source of fluid pressure, an auxiliary hollow plunger in said auxiliary cylinder communicating with the interior of said hollow plunger in front of the forward position of said second plunger therein, said auxiliary hollow plunger being connected with the first mentioned hollow plunger, means for controlling the communication between said first mentioned cylinder and source of fluid pressure to move the hollow plunger forward in its cylinder, means for controlling said communication to move the second plunger forward in said hollow plunger, means for controlling said communication to relieve the pressure in said cylinder, whereby said second source of fluid pressure moves said second plunger rearwardly in the hollow plunger and moves said hollow plunger rearwardly in its cylinder.

10. An upsetting press comprising a cylinder 95 communicating with a source of fluid pressure, a hollow plunger therein itself constituting a cylinder for a second plunger and communicating with the interior of said cylinder, a second plunger said 100 able in said hollow plunger, said hollow plunger having an annular die on the end thereof and said second die fitting snugly in the opening of said annular die and the faces of said dies being flush with each other 105 when said second plunger is in its rearmost position in said hollow plunger, means for controlling the communication between said cylinder and said source of fluid pressure to cause said hollow plunger to move forward 110 whereby both of said dies operate on the work, and means for controlling said fluid pressure to move said second plunger forward after the hollow plunger has completed its movement and is held against the periphery of the work.

11. An upsetting press comprising a cylinder 115 communicating with a source of fluid pressure, a hollow plunger in said cylinder itself constituting a cylinder for a second plunger and communicating with said first mentioned cylinder, a second plunger in said hollow plunger, means for holding a bar in position to be operated on by said plungers, means for controlling said communication between said cylinder and said source of fluid pressure to move said plungers forward to operate on said bar, means for controlling said communications to return said plungers and means for limiting the return 120 125 130 135 140 145 150 155 160 165 170 175 180

movement of said plungers, whereby said plungers are adapted to limit the feed of said bar.

12. An upsetting press comprising a cylinder communicating with a source of fluid pressure, a hollow plunger therein, the interior of said hollow plunger communicating with said cylinder, a second plunger in said hollow plunger, said plungers operating together to upset the end of a bar or the like and one of said plungers operating separately against said upset portion, and hydraulic clamping means for said bar, said means comprising a support for the work, a clamping cylinder, a clamping plunger therein movable against the work, an auxiliary clamping cylinder, an auxiliary plunger therein operatively connected with the clamping plunger in said clamping cylinder to move it away from the work, and means for controlling the hydraulic pressure in said clamping cylinder and said auxiliary clamping cylinder to cause said clamping plunger to engage said bar and to move 25 away therefrom.

13. A press composing a cylinder communicating with a source of fluid pressure, a hollow plunger therein, said hollow plunger having an opening in its back portion communicating with a source of fluid pressure, a packing in the end of said hollow plunger, a hollow nose piece secured to the end of said hollow plunger, said nose piece having openings therethrough, an annular die secured to said nose piece, a second plunger fitting snugly in said hollow plunger and movable lengthwise thereof, the end of said plunger fitting snugly in the hole in

said annular die and means for controlling the supply of fluid pressure to said cylinder and hollow plunger for operating both of said plungers.

14. A press comprising a frame including a plurality of longitudinally extending guide rods, a cylinder communicating with a source of fluid pressure, a hollow plunger therein, said hollow plunger having an opening in its back portion communicating with a source of fluid pressure, a packing in the end of said hollow plunger, a hollow nose piece secured to the end of said hollow plunger, said nose piece having openings therethrough and having projecting portions engaging said guide rods, an annular die secured to said nose piece, a second plunger fitting snugly in said hollow plunger and movable lengthwise thereof, the end of said plunger fitting snugly in the hole in said annular die and means for controlling the supply of fluid pressure to said cylinder and hollow plunger for operating both of said plungers.

15. A press comprising a cylinder, a hollow plunger therein, a second plunger in said hollow plunger, means for holding a bar or the like in position to be operated on by said plungers, said plungers being adapted and arranged to be operated together to upset the end of said bar and said second plunger being adapted and arranged to be operated alone to punch out a ring from said upset portion.

Signed at Oakmont, Pa., this seventh day of April 1921.

GOUVERNEUR GRAHAM BROWNE.
